UNITED STATES PATENT OFFICE.

GEORGE HENRY CAUGHREAN, OF KETCHIKAN, DISTRICT OF ALASKA.

COOKING DEVICE.

1,070,775.

Specification of Letters Patent.

Patented Aug. 19, 1913.

Application filed December 6, 1912. Serial No. 735,275.

To all whom it may concern:

Be it known that I, GEORGE H. CAUGHREAN, a citizen of the United States, and a resident of Ketchikan, in the District of Alaska, have invented certain new and useful Improvements in Cooking Devices, of which the following is a specification.

My invention relates to improvements in cooking devices, especially those in which fish, vegetables or other articles of food are to be heated in the cans in which they are packed, and it consists in the combinations, constructions and arrangements herein described and claimed.

An object of my invention is to provide a device of comparatively simple construction, in which a maximum number of cans may be treated to cook the contents in a minimum time.

A further object of my invention is to provide a cooking device having great economy in the heat needed for the cooking operation.

A further object of my invention is to provide a cooking device in which the cans are fed and discharged automatically.

Other objects and advantages will appear in the following specification and the novel features of the device will be pointed out in the appended claims.

My invention is illustrated in the accompanying drawings forming part of this application in which similar reference characters indicate like parts in the several views, and in which—

Figure 1 is a longitudinal sectional view through the device; Fig. 2 is a section along the line 2—2 of Fig. 1 looking in the direction of the arrow; Fig. 3 is a section along the line 3—3 of Fig. 1 looking in the direction of the arrows; Fig. 4 is a view of the upper end of the device; and, Fig. 5 is a transverse sectional view showing a portion of the heating tube.

In carrying out my invention I provide an inclined shaft 1, which is journaled in suitable bearings 2 and 3, which are carried by the upper and lower stationary plates 4 and 5 respectively. A series of tubes, such as those shown at A, B, C, etc., have their ends disposed in the stationary plates 4 and 5, these ends being expanded, as shown in Fig. 1, so as to secure the tubes firmly in position. Collars 4^x and 5^x are secured to the shaft in order to prevent longitudinal movement of the shaft with respect to the

plates or heads 4 and 5. The shaft 1, however, has a free rotary movement with respect to these heads.

Secured to the shaft by means of the set screw 6, or in any other suitable manner, is a revoluble plate 7 having an extension 8 arranged to be connected by means of a union 9 with a tube 10. The union 9 also permits the tube 10 to swivel or turn within the union during the motion of the extension. This tube 10, as will be seen from Fig. 2, extends upwardly and telescopes in another tube 11. The latter is supported at its top by means (not shown) which will permit it to have a slight movement from side to side. At the lower end of the shaft is a plate 12 which is similar in construction to the plate 7. It is provided with an outlet tube 13 connected by a union 14 with a discharge pipe 15. The plates 7 and 12 are so arranged that when the tube section 8 is in registration with any of the tubes, as for instance tube A, (see Fig. 1) the section 13 will be in registration with tube B. In Fig. 3 I have shown the general arrangement of the tubes which it will be seen are equal distances from the central shaft 1.

Each of the tubes A, B and C, etc., is surrounded by an outer tube, such as that shown at a, b, c, etc. The outer tubes are each provided with inlet pipes 16, by means of which steam may be admitted into the space between the inner and outer tubes. The bottoms of the outer tubes have drain pipes 17, 90 by means of which the water of condensation may be drawn off. These drain pipes 17 empty into a common discharge pipe 18. The outer tubes are lined preferably with some heat insulating material 19, such as asbestos, as shown in Fig. 5.

The plate 7 is provided with pins 20, which project through slots 21 in an annular plate 22. The latter is provided on its periphery with a series of ratchet teeth 23 arranged to be engaged by a pawl 24 at the lower end of a piston rod 25. The latter bears a spring 26 which keeps the pawl 24 in engagement with the ratchet teeth. The rod 25 may be reciprocated by any suitable means. The annular plate 22 is provided with a stop member 27, which is arranged to project into a slot 8^x in the tube section 8, when the plate 22 is moved in the manner hereinafter described. The device is supported by means of hangers 28, or it may be supported in any other suitable manner.

The plate 7 bears a spring 29, which engages a pin 30 on the annular plate or ring 22.

From the foregoing description of the various parts of the device the operation there-
5 of may be readily understood.

The cans of fish, vegetables or other material to be cooked are designed to be delivered by means of the pipes 11 and 10 into the tube section 8. Consider now Fig. 1; the tube 10 section 8 registers with the upper pipe A and, therefore, the cans may slide longitudinally into the pipe A until they are stopped by means of the plate 12. The rod 25 is now reciprocated and the pawl will be moved 15 from the full line position shown in Fig. 4 to the dotted line position. This will cause an initial movement of the annular ring or plate 22 until the ends of the slots 21 engage the pins 20. The effect of this initial move-
20 ment will be to cause the stop 27 to enter the tube section 8, thereby preventing the move-
ment of any more cans out of the tube 10 until the latter has been shifted to register with the tube B. As stated before, when the
25 tube section 8 is in registration with the pipe A the discharge tube section 13 is in regis-
tration with the pipe B and, therefore, the cans will have passed out of B into the dis-
charge pipe 15. When now the rod 25 is
30 further drawn upwardly the ends of the slots 21 will engage the pins 20 on the plate 7 and will, therefore, cause the revolution of the plate 7. Since this plate and also the plate 12 are firmly secured to the shaft, the
35 plate 12 will also be rotated to be brought into registration with the next tube C. Now on the retraction of the rod 25 the annular plate 22 will be rotated in the reverse direc-
tion far enough to permit the withdrawal of
40 the stop member 27, this being occasioned by the action of the spring 29. The friction of the parts will prevent the plate 22 from further backward revolution, while the pawl 24 is moving to the next tooth, or, if
45 desired, a dog may be provided to positively engage the teeth to prevent the backward revolution of the plate 22 when it has reached the end of the slot 21. The cans may now be delivered to the tube B, while
50 those which were in the tube C were of course discharged into the tube 15, when the latter came into registration with the tube C.

The reciprocation of the rod 25 is of course timed to allow the contents of the cans to be cooked. Obviously some articles require a longer and some a less time for cooking, and the rate of reciprocation of the rod 25 should be gaged accordingly.
60 The amount of steam, the pressure and temperature thereof may also be varied in accordance with the work to be done.

It will be apparent that as the plate 7 revolves to bring the tube section 8 into
65 registration with the various pipes the tube

10 will be drawn farther out of the tube 11 during one-half the revolution of the plate and will be forced into the tube 11 during the other half. As stated before the tube 11 is designed to have a slight pivotal movement from side to side so as to accommodate this movement of the tube 10. All that is necessary for the manipulation of this device is that the tube 11 should be supplied with cans which pass longitudinally through the tube 11 into the tube 10. When the reciprocation of the rod 25 is properly gaged the cooking of the contents of the cans is continued automatically and does not need any further attention.

I claim:

1. In a device for cooking canned food stuffs, a series of inclined tubes, a steam jacket for each tube, means for admitting steam into the jackets, means for draining the water of condensation from the jackets, a single delivery tube, means for bringing said single delivery tube into registration successively with said inclined tubes for charging the latter, and a telescopic supply pipe connected to said single delivery tube, the sections of said telescopic supply pipe being arranged to move relatively to one another to compensate for the movement of the delivery tube.

2. In a device for cooking canned food stuffs, a series of inclined tubes, a steam jacket for each tube, means for admitting steam into the jackets, means for draining the water of condensation from the jackets, a single delivery tube, means for bringing said single delivery tube into registration successively with said inclined tubes for charging the latter, a telescopic supply pipe connected to said single delivery tube, the sections of said telescopic supply pipe being arranged to move relatively to one another to compensate for the movement of the delivery tube, and a union for forming a swivel connection between said supply pipe and said single delivery pipe.

3. In a device for cooking canned food stuffs, a series of inclined tubes, a steam jacket for each tube, means for admitting steam into the jackets, means for draining the water of condensation from the jackets, a single delivery tube, and means for bringing said single delivery tube into registration successively with said inclined tubes for charging the latter.

4. In a device for cooking canned food stuffs, a series of inclined tubes, a steam jacket for each tube, means for admitting steam into the jackets, means for draining the water of condensation from the jackets, a single discharge tube, and means for bringing said single discharge tube into registration successively with said inclined tubes for discharging the latter.

5. In a device for cooking canned food

stuffs, a series of inclined tubes, a steam jacket for each tube, means for admitting steam into the jackets, means for draining the water of condensation from the jackets, 5 a single delivery tube, means for bringing said single delivery tube into registration successively with said inclined tubes for charging the latter, a single discharge tube, and means for bringing said discharge tube 10 into registration successively with said inclined tubes for discharging the latter.

6. In a device for cooking canned food stuffs, a pair of delivery plates, a series of inclined tubes having their ends secured in 15 said delivery plates, an inclined shaft arranged to extend through said delivery

plates, plates secured to said shaft, one of said plates being adjacent to the upper delivery plate and the other being adjacent to the lower delivery plate, a delivery tube carried by said upper revoluble plate and arranged to communicate with one of said inclined tubes, a discharge tube carried by said lower revoluble plate and arranged to register with an adjacent inclined tube, and 20 means for revolving said plates intermittently. 25

GEORGE HENRY CAUGHREAN.
